CLAIM

The ornamental design for a creeper with a collapsible chair, as shown and described.

DESCRIPTION

FIG. 1 is an isometric view of a creeper with a collapsible chair, showing my new design.

FIG. 2 is a right side elevation view of the design of FIG. 1, where the left side elevation view is a mirror image thereof.

FIG. 3 is a top plan view thereof.

FIG. 4 is a bottom plan view thereof.

FIG. 5 is a front elevation view thereof; and,

FIG. 6 is a rear elevation view thereof.

1 Claim, 4 Drawing Sheets

FIG.

FIG. 2

FIG. 3

FIG. 4

FIG. 5

FIG. 6
